UNITED STATES PATENT OFFICE.

ALBERT CECIL MEADY, OF SOMERVILLE, ASSIGNOR TO THE CROSBY STEAM GAGE AND VALVE COMPANY, OF BOSTON, MASSACHUSETTS.

STEAM-ENGINE INDICATOR.

SPECIFICATION forming part of Letters Patent No. 375,086, dated December 20, 1887.

Application filed July 25, 1887. Serial No. 245,203. (No model.)

To all whom it may concern:

Be it known that I, ALBERT CECIL MEADY, a citizen of the United States, residing at Somerville, in the county of Middlesex and 5 State of Massachusetts, have invented certain new and useful Improvements in Steam-Engine Indicators; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

15 Figure 1 is a top view, Fig. 2 a side elevation, Fig. 3 a vertical section, and Fig. 4 a horizontal section, of the drum, drum-spring, the paper-sustaining cylinder, and a portion of the arm supporting the parts mentioned of a steam-engine indicator having my 20 invention applied thereto. Fig. 5 is a side elevation of the drum.

My invention consists in forming the drum with a vertical groove in its side to receive a 25 vertical ridge formed on the interior surface of the paper-sustaining cylinder, said cylinder also having a vertical groove formed in its outer surface directly opposite the ridge on its interior to receive an arm pivoted to a 30 head secured to the lower part of the paper-sustaining cylinder, said arm at its upper end to operate a spring-latch and be held by it in contact with the groove.

In the drawings, A denotes the arm of the 35 indicator, which supports the spindle a, on which the reciprocating drum B is sustained, the drum having secured to its head the spring S, and the spring being applied to the top of the spindle in the usual manner, 40 as shown. The said drum I provide with a vertical groove in its periphery, as shown at b, to receive a vertical ridge, c, projecting inward from the interior surface of the paper-sustaining cylinder C, said groove and ridge 45 serving to couple the drum and cylinder together.

The cylinder C is made of thin metal, as shown, and the ridge c is formed by forcing

in a narrow portion of its outer surface throughout the entire length of it toward the 50 axis of the cylinder, thus forming at one and the same time a ridge on its interior surface and a groove in its outer surface, as shown at d. In said groove I arrange an arm, D, which is pivoted at its lower end at f to a head, E, 55 secured to the cylinder C by screws e e, which enter the lower portion of the groove d.

Near the upper part of the ridge c is secured a spring, g, provided with a catch, h, which, when in the position shown in Fig. 3, 60 securely holds the arm D in contact with the groove d.

The purpose of my invention is to provide a convenient and efficient means of securing to the surface of the cylinder C a sheet of paper to be operated upon by the marker of the indicator when using said indicator to ascertain the pressure of steam in the cylinder of the engine at different points of the stroke of its piston.

70 By lifting the catch h and swinging the arm D into the position shown in dotted lines in Fig. 3, and applying to the surface of the drum a sheet of paper, so as to envelop the same and have each end of the sheet lap past 75 the other end in front of the groove d, as shown in Fig. 2, then, by swinging the said arm under the catch and into the groove into the position shown in full lines in Fig. 3, I shall have a sheet of paper properly secured 80 to the cylinder to be used for the purpose indicated.

Having described my invention, what I claim in a steam-engine indicator is—

1. The cylinder C, provided with the ridge c 85 and groove d, as shown, the head E, secured to said cylinder by screws entering in said groove, and having the arm D pivoted thereto, and the spring g, formed with a catch to hold the arm in contact with the groove, in combination with the reciprocating drum B, having a groove, b, to receive the said ridge c, all essentially as set forth.

2. The cylinder C, provided with the ridge c and groove d, as shown, the head E, secured 90 to said cylinder by screws entering the said

groove, and having the arm D pivoted thereto, and the spring g, formed with a catch to hold the arm in contact with the groove, in combination with the reciprocating drum B, having a 5 groove to receive the ridge of the cylinder C, the spring S, spindle a, and arm A, all being arranged and to operate substantially as shown and described.

In testimony whereof I affix my signature in presence of two witnesses.

ALBERT CECIL MEADY.
